UNITED STATES PATENT OFFICE.

JAMES JACOBSON, OF NEW YORK, N. Y.

DESIGN FOR TRIMMING.

SPECIFICATION forming part of Design No. 22,858, dated October 31, 1893.

Application filed June 3, 1893. Serial No. 476,526. Term of patent 3½ years.

To all whom it may concern:

Be it known that I, JAMES JACOBSON, of New York city, in the county and State of New York, have invented and produced a new 5 and original Design for Fur Trimming, of which the following is a specification.

Reference is to be had to the accompanying drawings forming a part of this specification in which—

10 Figure 1 represents in perspective a piece of trimming embodying my new design; and Fig. 2 represents a cross section thereof.

The leading or characteristic features of the design consist in a strip as shown, the same

being ruffled and presenting reversed, approximately curved loops at the side edges, the lines of the strip at such side edge being returned, such returned edges following the lines of the loops and presenting undulating furry figures, the furry lines of such figures 20 being approximately radially disposed.

I claim—

The design for a trimming herein shown and described.

JAMES JACOBSON.
